UNITED STATES PATENT OFFICE.

GEORGE M. TALBERT AND HARRY DAVIS, OF LOS ANGELES, CALIFORNIA.

INSECT-EXTERMINATOR.

1,361,293.

Specification of Letters Patent.

Patented Dec. 7, 1920.

Application filed August 25, 1919. Serial No. 319,809.

To all whom it may concern:

Be it known that we, GEORGE M. TALBERT and HARRY DAVIS, both citizens of the United States, residing at Los Angeles, in the county 5 of Los Angeles and State of California, have invented certain new and useful Improvements in Insect-Exterminators, of which the following is a specification.

Our invention relates to insect exterminators of the type employing a tank containing sulfur or other insecticide, and pneumatic means for blowing or spraying such insecticide into trees, plants and the like.

One object of the invention is to provide 15 a screen in the powder tank above the outlet passage to support the weight of the powder, to employ a cleaner for said screen operating over the latter to permit the powder to effectively discharge there- 20 through and to provide an agitator below the screen for loosening the powder discharged therethrough, so that it will be effectively blown out by the air current.

Another object of the invention is to provide 25 novel means for operating the screen cleaner and the agitator from the mechanism employed for actuating the means which is used for forcing currents of air through the powder discharge passage.

With the foregoing in view, the invention resides in the novel construction and arrangement of parts hereinafter described and claimed, the descriptive matter being 30 supplemented by the accompanying drawing.

Figure 1 is a side elevation of an insect exterminator constructed in accordance with our invention.

Fig. 2 is a bottom plan view.

Fig. 3 is a vertical section on the plane 40 of the line 3—3 of Fig. 2.

Fig. 4 is a detail perspective of the screen cleaner and its operating shaft.

Fig. 5 is a detail vertical sectional view as indicated by line 5—5 of Fig. 2.

In carrying out our invention we employ 45 a powder tank 1 having a powder delivery passage 2 at its lower end; a bellows or other suitable means 3 for forcing currents of air through said passage 2; a screen 4 in the tank 1 to support the weight of the powder; a cleaner 5 for preventing clogging of the screen 4; an agitator 6 below the screen for loosening the powder discharged therethrough; and manually actuated means for 50 operating the air supply means 3, the cleaner 5, and the agitator 6.

In the preferred form of our invention, the bottom 7 of the tank 1 is of funnel shape and the delivery passage 2 consists of a fixed pipe into which said hopper-like bottom discharges, and a flexible hose 9 having a suitable nozzle 9^a. The part 8^a of the aforesaid pipe leads from the bellows 3 to the hopper 7 and the portion 8 of said pipe leads from said hopper to the hose 9, and whenever a blast of air is directed through 60 said pipe by said bellows it will carry with it a quantity of the insecticide from the hopper.

The agitator 6 and screen cleaner 5 may 70 be of any adequate form and actuated by suitable means, but we prefer to mount both of these parts on a single vertical shaft 10 which depends a slight distance from the tank bottom 7. The upper end of this shaft 75 is preferably provided with a vertical slot 11 and the screen cleaner 5 may well be formed from a single strip of metal held in said slot by a nut 12, said strip being slightly twisted at opposite sides of the shaft 80 10 to hold it against endwise shifting and to provide oppositely extending cleaning arms 13 whose flat sides incline downwardly to the screen 4 for effectively cleaning the latter when the shaft is turned. By con- 85 structing and mounting the cleaner 5 in the manner shown, it may be easily and inexpensively manufactured, yet will be highly efficient in use.

The agitator 6 is by preference formed 90 from a single horizontal piece of wire, centrally attached to the shaft 10 and provided with downturned ends 14 positioned adjacent the bottom 7. This agitator, how- 95 ever may vary in form as occasion may dictate.

The lower end of shaft 10 is shown pro- 100 vided with a ratchet wheel 15, and an arm 16 is pivotally mounted on said shaft adjacent said wheel, said arm carrying a spring 105 pressed pawl 17 coacting with said wheel to intermittently rotate the shaft 10 when said arm is oscillated. This oscillation may be accomplished in numerous ways but we prefer- 110 ably connect the arm 16 by suitable link- age 18 to a lateral arm 19 on a rock shaft 20 which is employed for operating the bellows or the like 3. This shaft is shown provided with a suitable hand lever 21 and with upstanding crank arms 22, the latter 110 being pivoted to the ends of a bail 23 which is connected with the pivoted half of the

bellows. The shaft 20 may be mounted in any preferred manner but is preferably carried by a metal strap or band 24 which surrounds the lower portion of the tank 1 and 5 is secured to the fixed part of the bellows.

Suitable shoulder straps 25 and back rest 26 are shown so that the entire device may be carried easily on the user's back, with the nozzle 9^a in convenient reach of one hand and 10 the lever 21 accessible for operation by the other. When this lever is oscillated, the shaft 20 is rocked to operate the bellows 3 and at the same time the connections 19, 18, 16, 17, and 15, come into play to intermittently 15 rotate the shaft 10. Rotation of this shaft causes the cleaner 5 to move over the screen 4, thus preventing the powder from clogging upon the screen and allowing a quantity of such powder to fall into the space 20 between the screen and the bottom 7. This powder is stirred and loosened by the agitator 6 and is deposited in this loose condition into the pipe 8—8^a. In this pipe, the powder is picked up by the air blast from 25 the bellows 3 and carried through the hose 9 to be discharged from the nozzle 9^a. Particular emphasis is laid upon the fact that the screen 4 supports the weight of the powder and that only a small quantity of this 30 powder is allowed to discharge into the passage 2 at each operation of the bellows or the like 3. By this arrangement, packing of the powder in the delivery passage 2 and consequent clogging of such passage is prevented.

35 The entire device is simple and inexpensive, has been actually used, and has proven highly efficient and desirable in every way, and since probably the best results are obtained from the details disclosed, they may 40 well be followed. We wish it understood however that within the scope of the invention as claimed, the device may be embodied in numerous forms other than that shown.

We claim:

45 1. An insect exterminator comprising a powder tank provided with a powder delivery passage, air supply means discharging into said passage, a powder supporting

screen in said tank above said passage, an agitator below said screen, means in contact with the upper side of said screen for scraping the powder from the latter, lifting such powder, and dropping it loosely upon said screen, and means for simultaneously actuating said air supply means, said agitator, and said powder scraping, lifting and dropping means. 50 55

2. An insect exterminator comprising a vertically disposed powder tank having a funnel shaped bottom spaced upwardly from the lower end of its wall, the portion of said wall below said bottom forming a depending skirt, powder feeding means in the bottom of said tank, a vertical shaft on which said feeding means is mounted, said shaft 60 extending through the tank bottom and having a ratchet wheel, a dog coacting with said ratchet wheel, an oscillating arm mounted on said shaft and carrying said dog, a transverse rock-shaft extending across the aforesaid apron and having a depending crank arm adjacent the latter, linkage connecting said crank-arm with said oscillating arm, a powder discharge passage extending across said skirt and communicating with the lower 65 end of the tank, a bellows at one side of said tank discharging into said passage, and means for operating said bellows from said rock shaft. 70 75

3. An insect exterminator comprising a 80 powder tank having a horizontal powder supporting screen and a powder discharge passage below said screen, means for supplying forced currents of air through said passage, a driven vertical shaft adjacent the 85 center of said screen and having a longitudinal slot, and a flat strip of metal received at its center in said slot, said strip being twisted on opposite sides of said shaft to hold it against endwise shifting and to provide flat screen cleaning arms whose flat sides incline downwardly to said screen. 90

In testimony whereof we affix our signatures.

GEORGE M. TALBERT.
HARRY DAVIS.
